UNITED STATES PATENT OFFICE.

ENOCH RENSLOW ROLFE HOYT, OF PHILADELPHIA, PENNSYLVANIA.

STEAM-BOILER FURNACE.

SPECIFICATION forming part of Letters Patent No. 729,589, dated June 2, 1903.

Application filed June 30, 1902. Serial No. 113,725. (No model.)

To all whom it may concern:

Be it known that I, ENOCH RENSLOW ROLFE HOYT, a citizen of the United States, and a resident of Philadelphia, county of Philadelphia, and State of Pennsylvania, have invented certain new and useful Improvements in Steam-Boiler Furnaces, of which the following is a specification, reference being had to the accompanying drawings, forming a part thereof, in which similar letters of reference indicate corresponding parts.

This invention relates to steam-boiler furnaces, the object thereof being to provide an improved structure of this character adapted to promote perfect or approximately perfect combustion and prevent smoke or reduce its volume to a minimum, and which is so constructed as to supply heated air to the furnace to insure uniformity of temperature of the air admitted thereto for purposes of supplying the oxygen necessary for combustion of the fuel employed, and in which the carbon produced by combustion is combined with the heated oxygen to generate carbon dioxide or carbonic acid, whereby combustion of the fuel is accelerated.

The device is simple in construction, economical and generally efficient in operation, and it is adapted to burn any common fuel and is especially applicable for practicably consuming bituminous or other soft smoke-producing coal.

The invention will be hereinafter fully described, and specifically set forth in the annexed claims.

In the accompanying drawings, forming part of this specification, Figure 1 is a longitudinal sectional elevation of a boiler and furnace having my improvements forming part thereof. Fig. 2 is a detail sectional plan view taken in the line $\alpha\alpha$ of Fig. 1, and Fig. 3 is a detail vertical sectional elevation taken on the line yy of Fig. 1.

In the practice of my invention I may employ in connection with my improvements any common and well-known furnace and boiler structure. For purposes of illustration I have shown in the drawings a furnace A, having walls of ordinary construction and containing the grate B, water-reservoir C, steam-reservoir C', and mud-drum D.

The bridge E of the furnace is of novel con-

struction and embodies the two walls $e\ e'$, having the compartment F between them, the front wall e' having the passage or flue E' for inlet of air below the grate. The top of this compartment is closed by means of the removable plate G, which has an opening g for outlet of heated air to be supplied to the furnace, as will be hereinafter fully described. Within and extended laterally across the compartment F and embedded in the side walls of the furnace I place a plurality of vertical partitions H H'. These partitions are preferably equidistant and parallel with each other, and they preferably embody flat plates composed of any suitable material adapted to withstand the action of heat; but I do not confine myself to their specific surface contour nor arrangement, as they might be arranged in positions other than vertical. The plates H each extend to a point near the bottom of the compartment F and are respectively tightly fitted to the cover G to form an air-tight joint, and the plates H' respectively extend from a tight joint at the bottom to a point near the top of the compartment. Thus a zigzag or tortuous channel is provided which admits the air which enters through the flue E' to be heated during its winding course through the compartment F.

In the operation and use of the invention atmospheric air or any other medium adapted to assist combustion is introduced through the channel E to the compartment F, and the draft causes the air to pass alternately in a downward and upward direction through the tortuous channel formed by the plates H H' until it is finally discharged through the outlet-opening g into the furnace proper, heated to a uniformly high temperature owing to its slow tortuous course through the compartment F. Having entered the furnace with its temperature uniformly raised, the said medium readily combines with the carbon or other combustible elements thrown off by the fuel, thus promoting combustion and preventing smoke.

I do not confine myself to the specific details of construction and contour of the parts as herein shown and described, as it is obvious that under the scope of my invention I am entitled to slight structural variations.

Having thus described my invention, what

I claim as new, and desire to secure by Letters Patent, is—

1. In a steam-generator furnace, the combination with a bridge-wall, located beneath the grate of said furnace, and having a compartment therein, and having its forward wall pierced with an air-inlet, of parallel vertical plates embedded in the walls of said compartment and arranged to form a tortuous 5 passage in said compartment, whereby the media to be heated and supplied to the furnace is first conducted downward, then upward, and so alternately downward and upward, until it passes into the combustion-10 chamber of the furnace, and a removable plate formed with an opening for the passage of media from said compartment into the said combustion-chamber, resting on and closing the top of said compartment.
2. In a steam-generator, the combination 15 with a water-reservoir C, a furnace A, and a

bridge E, formed with the compartment F, and the inlet E', in the middle of the forward wall thereof, of the vertical plates H and H', embedded in the walls of said compartment, 25 extending within said compartment, arranged to conduct media to said furnace through a tortuous channel, and to heat the same, while being so conducted, and a removable plate G, covering said compartment and constructed 30 with the outlet g', through which said media, after being conducted through the said tortuous passage in said compartment, passes into the combustion-chamber of said furnace.

In testimony that I claim the foregoing as 35 my invention I have signed my name, in presence of two witnesses, this 24th day of April, A. D. 1902.

ENOCH RENSLOW ROLFE HOYT.
